United States Patent

Des. 239,641

Patented Apr. 20, 1976

239,641

LOWER BUTTOCKS AND HAMSTRING EXERCISING MACHINE

Robert Clarke, Pacific Beach, Calif., assignor to Paramount Health Equipment Corp., Los Angeles, Calif.

Filed June 24, 1974, Ser. No. 482,099

Term of patent 14 years

Int. Cl. D21—02

U.S. Cl. D34—5 K

FIG. 1.

FIG. 2.

FIG. 1 is a right front perspective view of a lower buttocks and hamstring exercising machine showing my new design; and

FIG. 2 is a left rear perspective view thereof.

I claim:

The ornamental design for a lower buttocks and hamstring exercising machine, as shown.
